UNITED STATES PATENT OFFICE.

ARTHUR E. MOORE, OF CONIMICUT, RHODE ISLAND, ASSIGNOR TO REX MANUFACTURING CO., OF PROVIDENCE, RHODE ISLAND, A CORPORATION OF RHODE ISLAND.

MECHANICALLY-OPERATED PENCIL.

Application filed July 14, 1925. Serial No. 43,575.

To all whom it may concern:

Be it known that I, ARTHUR E. MOORE, a citizen of the United States, residing at Conimicut, in the county of Kent and State 5 of Rhode Island, have invented certain new and useful Improvements in Mechanically-Operated Pencils, of which the following is a specification.

This invention relates to an improvement 10 in the construction of mechanically-fed lead pencils, and has for its object to provide in such a pencil a barrel portion having a point sleeve bushing secured at one end thereof and a frusto conical sleeve formed 15 separate and independent of the bushing and secured thereon by a point end member adjustably held in the end of the bushing.

With these and other objects in view, the 20 invention consists of certain novel features of construction, as will be more fully described, and particularly pointed out in the appended claims.

In the accompanying drawings:

Figure 1 is a side elevation of my improved pencil showing the pointed end partly broken away to better illustrate my improved construction.

Figure 2 is a detail of the point sleeve bushing in section.

Figure 3 is a detail of the frusto-conical sleeve in section.

Figure 4 is a detail of the point end member in section.

Heretofore in the forming of the pointed 35 end portion of a pencil where the precious-metal conically-shaped sleeve was of the full length of the tapered portion and drawn substantially to a sharp point, it was found in practice that this reduced end portion of 40 many of the sleeves in hammering them down so fine were injured and a large percentage became imperfect and so lost. To obviate this difficulty, I have shortened this sleeve member at its point end thus reducing 45 its cost and loss by waste, I have provided a shouldered point end member of non-rusting material such as nickel silver and the like and have threaded this member into the bushing with its shoulder engaging the adjacent end of the sleeve, whereby the shortened sleeve is gripped and bound against the end of the barrel portion, by which construction the cost of assembling the parts is reduced and may be done very rapidly 50 without soldering and when assembled this

point-end member in binding the sleeve against the body of the pencil also serves to bind the screw portions of the end member in its bushing and the bushing in its barrel portion, and the following is a detailed description of the present embodiment of my invention and showing one construction of pencil by which these advantages results may be accomplished:—

With reference to the drawings, 10 designates the barrel or body portion of a pencil, which may be made of any suitable material, but which is preferably made of a rubber composition tubing cut to the desired length, the tubing may also be made in a 15 variety of colors to vary the appearance of the pencils.

This tubing adjacent the pointed end of the pencil is internally threaded as at 11 and a so-called point sleeve bushing 12 is 20 formed preferably of base metal having a threaded shank portion 13 adapted to be screwed into the threaded end of the barrel. This bushing is frusto-conical in shape having a central bore 14 for the reception of a 25 spring 18 and other lead-operating members and is threaded at its lower end 15.

Fitted over this bushing member is a sleeve 16 of frusto-conical shape. This 30 sleeve may be formed of any of the precious metals and is preferably of a length greater than the body portion of the bushing so that its lower end portion 17 will extend beyond the corresponding end of the bushing.

In order to lock these parts together, I 35 have provided a point end bushing 19, the body of which is drawn to a fine end as at 20 through which the lead 21 projects and this member is provided with a shank portion 22 threaded at its upper end to screw 40 into the threaded portion 16 of the bushing thus providing a shoulder 23 on this member against which rests the reduced lower end of the sleeve so that when this member is screwed into the bushing it serves to bind 45 the opposite end of the sleeve against the end of the barrel portion of the pencil and when this member is set up tightly, the sleeve serves as a check nut to bind the threaded portion of this member in the 50 lower end of the bushing and also the threaded portion of the bushing tightly in its threaded engagement with the barrel thus locking all of these end parts firmly together.

By my improved construction the sleeve member may be made in frusto-conical shape and by forming the sleeve in this shape without drawing it down to a fine pointed end, obviates the most delicate portion of the hammering operation in the forming of this sleeve and thus eliminates a large portion of the heretofore wasted precious metals, due to imperfect work in trying to draw 10 down the tube end to so fine a point; also by this construction of threading the point end member into the bushing member this sleeve member is readily bound in position over its bushing; also this point end member by its special construction is a screw-machine product and is, therefore, quite inexpensive to produce.

Further, but this construction of binding the sleeve between the point end member and 20 the body of the pencil the necessity of a soldering operation is eliminated.

The foregoing description is directed solely towards the construction illustrated, but I desire it to be understood that I reserve the privilege of resorting to all the mechanical changes to which the device is susceptible, the invention being defined and limited only by the terms of the appended 25 claims.

20 I claim:

1. In a mechanically-operated pencil, a barrel portion, a point sleeve bushing secured to one end thereof, a tapered sleeve fitted over the bushing having one end 35 shouldered against the barrel, and a point end member secured to said bushing and provided with a shoulder for engaging the

adjacent end of said sleeve by which the sleeve is held against the barrel.

2. In a mechanically-operated pencil, a 40 barrel portion, a point sleeve bushing secured in one end thereof, a tapered sleeve over the bushing having one end shouldered against the barrel and a point end member having threaded engagement with 45 said bushing and provided with a shoulder engaging the adjacent end of the sleeve to bind it against the barrel.

3. In a mechanically-operated pencil, a 50 barrel portion, a tapered point sleeve bushing adjustably secured to one end thereof, a frusto-conical sleeve over the bushing having one end abutting against the barrel, and a point end member having threaded engagement with said bushing and provided 55 with a shoulder to abut against the end of the sleeve to bind it against the barrel portion.

4. In a mechanically-operated pencil, a 60 barrel portion, a tapered point sleeve bushing threaded into one end of said barrel, a frusto-conical sleeve positioned over the bushing with its end portion extending beyond that of said bushing, and a point end member having a shank portion threaded 65 into said bushing and provided with a shoulder portion engaging the extended end of said conical member, whereby the setting up of the point member binds the sleeve against the barrel and the bushing threads in the 70 barrel.

In testimony whereof I affix my signature.

ARTHUR E. MOORE.
